UNITED STATES PATENT OFFICE.

JOHN BENNET WEBSTER, OF LOS ANGELES, CALIFORNIA.

WATER-HEATER.

SPECIFICATION forming part of Letters Patent No. 289,194, dated November 27, 1883.

Application filed April 4, 1883. (No model.)

To all whom it may concern:

Be it known that I, JOHN B. WEBSTER, of Los Angeles, in the county of Los Angeles and State of California, have invented a new and Improved Water-Heater, of which the following is a full, clear, and exact description.

The object of my invention is to provide a portable heater that can be readily and conveniently used for heating small and large quantities of water in houses where water-backs and hot-water boilers are not applied, and in other places in or out of doors where hot water is needed—for instance, by stablemen, dairymen, farmers, and others.

15 The invention consists of the combination and arrangement of parts, substantially as hereinafter fully set forth and claimed.

Reference is to be had to the accompanying drawings, forming a part of this specification, 20 in which similar letters of reference indicate corresponding parts in all the figures.

Figure 1 is a side view, in perspective, of the heater. Fig. 2 is a similar view at right angles to Fig. 1. Fig. 3 is a horizontal section 25 of the heater, and Fig. 4 is a sectional elevation of the same.

The chamber or body A of the heater is constructed of sheet metal, with flaring sides and with a broad base, a. In one side is an 30 opening provided with a screw-cap, b, packed, to make it water-tight, and which gives access to the burner for lighting. The closed top c of the body (shown most clearly in Fig. 3) is of copper, and provided with tubes d, 35 preferably four in number, and equidistant, which extend from the outer edge of the top inward and upward to a tube or pipe, e, which is the chimney, and is of suitable length. In the top c, between tubes d, are holes, two between 40 each pair of tubes, that are covered by tight boxes f, from which short tubes g extend to the chimney e, below tubes d, so as to form an inner set of tubes, that will become highly heated by the flames. To the opposite sides 45 of the body A are connected tubes h, which extend upward a suitable distance, but are shorter than the chimney. These tubes h are for supplying air to the burner, and should be large enough to insure the burning of the 50 oil with a strong blue flame. On their upper ends are deflectors h', for catching the air from

all sides and turning it down the tubes. On the chimney e is a chimney-cap, e', for promoting draft.

The burner, which may be an oil-burner 55 similar to a vapor-burner or the burners of oil-stoves, is contained in the body A, connected to a pipe, i, that extends in through the side, and to the outer end of pipe i is connected a vertical pipe, k, from a reservoir, l. 60 m is a foot at the lower end of pipe k, for support of the reservoir.

The whole apparatus is constructed of sheet metal, with all joints riveted or soldered tightly, to prevent access of water to the interior. 65 Around the edge of the top c is a rim, n, so that water can be placed on the top covering the joints of the tubes, to prevent the heat from opening the joints when the heater is not submerged.

To heat a quantity of water with this heater, oil or gasoline is to be placed in the reservoir, cap b unscrewed for lighting the burner, and the cap replaced after the flame is properly regulated. The heater is then to be 75 placed on the bottom of a receptacle containing the water to be heated, which may be a tub, half-barrel, or boiler, though a deep and narrow receptacle is preferable, in order to get the body of water above the heater. 80

With the construction of the heater as described (the copper top part, c, being directly affected by the several strong blue jets of flame, and constituting the principal heating agent) the body and tubes become highly 85 heated by the flames, and the water having access to an extensive heating-surface, but a short time is required to boil or heat the water.

The operation can be readily carried out in the house or elsewhere without dirt or smoke, 90 and water heated for bathing purposes, for farm and other operations, at less expense and trouble than by the usual way upon a stove or over a fire out of doors.

The apparatus is inexpensive, and is to be 95 made of any suitable size.

Having thus fully described my invention, I claim as new and desire to secure by Letters Patent—

1. In water-heaters, the combination, with 100 the closed heating-chamber A, of the two series of convergent pipes g d, connecting with a

common smoke-exit, one series being arranged below or above the other, substantially as and for the purpose set forth.

2. In a water-heater, the heating-chamber having the smoke and draft tubes, and the closed top provided with a vertical rim or flange, said closed top forming the bottom and said flange forming the sides of a supplemental or upper open water-chamber, substantially as to and for the purpose set forth.

3. The water-heater consisting of closed body A, containing an oil-burner, chimney e, connecting-tubes d g, supply-pipes h, oil-reservoir l, and oil-pipe k, combined and arranged substantially as described.

JOHN BENNET WEBSTER.
